(57) **CLAIM**

The ornamental design for a caddy, as shown and described.

DESCRIPTION

FIG. 1 is a front perspective view of a caddy, in accordance with my new design.

FIG. 2 is a bottom perspective view of the caddy, in accordance with my new design.

FIG. 3 is a front view of the caddy, in accordance with my new design.

FIG. 4 is a back view of the caddy, in accordance with my new design.

FIG. 5 is a left end view of the caddy, in accordance with my new design.

FIG. 6 is a right end view of the caddy, in accordance with my new design.

FIG. 7 is a top view of the caddy, in accordance with my new design.

FIG. 8 is a bottom view of the caddy, in accordance with my new design; and,

FIG. 9 is a front perspective view of the caddy showing the removable panels in the ends of the caddy, in accordance with my new design.

In the drawings, the broken lines indicate portions of the article including stitching, and environmental structure that form no part of the claimed design.

1 Claim, 8 Drawing Sheets
